HENRY MILLER

UNITED STATES PATENT OFFICE.

HENRY MILLER, OF BRISTOL, PENNSYLVANIA.

BRAKE-BEAM HANGER.

1,239,206.

Specification of Letters Patent.

Patented Sept. 4, 1917.

Application filed October 10, 1916. Serial No. 124,879.

To all whom it may concern:

Be it known that I, HENRY MILLER, a citizen of the United States, residing at Bristol, in the county of Bucks and State of Pennsylvania, have invented certain new and useful Improvements in Brake-Beam Hangers, of which the following is a specification.

This invention relates to a brake beam hanger and the principal object of the invention is to provide an improved type of carrying bar with which the chain carrying the brake beam engaging clevis or bracket is connected and to further provide a hanger so constructed that the same will be very strong and durable and the brake beam supported and guided in its movement but permitted to have the proper movement and play when moving into and out of engagement with the car wheels.

This invention is illustrated in the accompanying drawings, wherein:—

Figure 1 is view in elevation of the improved hanger.

Fig. 2 is a sectional view taken along the line 2—2 of Fig. 1.

The carrying bar 10 is provided with a shoulder 11 intermediate its length and has one end portion 12 squared in cross section and provided with a depending eye 13 extending beneath a cutout 14 in the under portion of the bar. In the opposite end portion of the bar, there is provided an opening 15 through which a securing device may pass to hold the bar in place. The bracket 16 which engages the brake beam is provided with upper and lower arms 17 and 18 having openings in their ends to receive the bolt 19 which in its turn is held in place by means of the cotter pin 20. The upper arm 17 carries an eye 21 with which is connected the chain 22 carried by the eye 13. It will thus be seen that with this improved device, the brake beam can be supported and permitted

to have the proper movement toward and away from the wheels. At the same time, 45 the movement of the brake beam will be guided, it being of course understood that one of the devices will be positioned adjacent each end of the brake beam.

What is claimed is:—

1. A brake beam support comprising a carrying bar provided with a vertically extending shoulder intermediate its length and having its outer end portion provided with a depending eye extending beneath a cutout 55 formed in the outer end portion, a brake beam engaging element, and flexible means connecting the brake beam engaging element with the eye of said carrying bar.

2. A brake beam support comprising a carrying bar provided adjacent one end with a depending eye extending beneath a cutout formed in the bar, a brake beam engaging element and flexible means connecting the brake beam engaging element with the eye 65 of said carrying bar.

3. A brake beam support comprising a carrying bar provided with an eye adjacent one end, a clamp provided with an eye, and flexible means having one end connected 70 with the eye of said clamp and the second end connected with the eye of said carrying bar.

4. A brake beam support comprising a carrying bar provided with an eye, a clamp 75 having spaced arms, a securing device carried by the arms, an eye extending from one of said arms, and a chain connected with the eye of said carrying bar and with the eye of said arm.

In testimony whereof I affix my signature in presence of two witnesses.

HENRY MILLER.
